UNITED STATES PATENT OFFICE.

JOHN ARTHUR TORRENS, OF SOMERSET, COLERAINE, IRELAND.

ELECTRICAL IGNITION APPARATUS.

No. 908,906.

Specification of Letters Patent.

Patented Jan. 5, 1909.

Application filed September 17, 1907. Serial No. 393,343.

To all whom it may concern:

Be it known that I, JOHN ARTHUR TORRENS, a subject of the King of Great Britain, residing at Somerset, Coleraine, in the county 5 of Londonderry, Ireland, major, late of "Scots Greys," have invented certain new and useful Improved Electrical Ignition Apparatus, of which the following is a specification.

10 This invention consists in an improved electrical ignition apparatus which is designed particularly for internal combustion engines but may be applied to other purposes.

15 The improved apparatus is of the low tension type in which the spark is produced at the electrodes by breaking at that point a circuit of very considerable self induction which has been momentarily closed by any 20 suitable means actuated by the engine so as to energize an electromagnet, the resultant movement of the armature of which is caused to deflect or displace a movable electrode included in the circuit from contact with a 25 fixed electrode and thereby produce a spark at the gap.

25 The improved construction of such apparatus which constitutes the present invention is illustrated in elevation in Figure 1 and 30 in longitudinal section in Fig. 2 of the accompanying drawings, Figs. 3 and 4 being detail views respectively of the preferred terminal connection and the end of the movable electrode.

35 As therein shown the movable electrode *a* is not connected positively with the magnet armature and consequently the contact pressure of the spark electrodes *a*, *b* is not diminished by reason of the attraction of the magnet 40 net before contact is actually broken, and consequently the so-called "extra current" on breaking the circuit is not thereby reduced.

45 The electro-magnet *c* is of the closed iron-clad or concentric cylinder pattern with the armature *d* forming a lid, a construction which, with the tubular extension of the inner cylinder *c'* of the electromagnet and the tubular shell of the plug *e* allows the working 50 parts to be practically entirely inclosed and consequently protected from accession of dirt and failures resulting therefrom.

55 The armature *d* is secured on a non-magnetic plunger *f* working practically dust-tight in the central bore of the magnet and normally urged by a spring *f'* into a position

in which a striking rod *g* carried by the plunger is clear of the coöperating surface of the movable electrode *a*. The striking rod *g* is preferably of steel case hardened at its inner 30 end and extends axially through the plunger *f* which is hollow and in which it is secured so as to be adjustable longitudinally therein, as by means of the screwed bush *g'* and lock-nut *g''*.

35 The movable electrode with which the striker coöperates is fulcrumed within a non-magnetic tubular extension *h* of the inner cylinder of the magnet, which projects into the tubular body of the sparking plug *e* but is insulated therefrom by a sleeve *e'* of suitable material which is locked in position within the internally screw threaded body of the sparking plug by means of an externally screw threaded sleeve or bush *e''* fitting 75 therein.

40 The electrode fulcrum is preferably constituted by a ball and socket joint or bearing *h'*, *a'* which takes the thrust of the pressure of the working fluid and prevents leakage there- 80 of and the pivot of which is preferably in axial alinement with the striking rod *g*. The axis of the electrode *a* is disposed at a small angle with the striker and is urged to aline 85 itself therewith by means of a coil spring *i* which encircles the outer part of the electrode and is compressed between a fixed abutment *i'* and a sliding sleeve *i''* thereon which sleeve is thereby urged against a fixed 90 coöperating abutment such as the rear face *h''* of the fulcrum socket *h'* so as to tend to turn the electrode upon its fulcrum into alinement with the striking rod thereby 95 maintaining a considerable pressure on the contact surfaces of the movable and fixed electrodes. These contact surfaces are separated by the movable electrode being turned upon its fulcrum against the action of the returning spring, this displacement causing the sliding abutment to be thrust along the electrode thereby compressing the spring still 100 more.

45 The electrode is displaced to separate the contacts by the blow of the inner end of the striking rod *g* upon a suitable inclined surface 105 on the outer end of the electrode, and this inclined surface is preferably constituted by the bottom of a radial groove *j'* formed in a crown piece *j* detachably secured to the outer end of the movable electrode. There 110 are usually provided a plurality of such radial grooves *j'* equally spaced around the

axis of the electrode in correspondence with an equal number of platinum contact studs a^3 similarly spaced around the detachable inner end a' of the movable electrode preferably on a spiral line, such studs coöperating with an elongated platinum strip or anvil b' on the fixed electrode, which is detachably secured within the sparking plug in proper relation with the movable electrode. This arrangement enables a fresh pair of sparking contacts to be brought into use with great facility.

The magnet is arranged to be detachable from the plug part of the device by simply easing a clamping screw k by which the inner cylinder c' is secured to the tube h , or freeing a bayonet joint uniting the two parts, so that access may be obtained to the movable electrode either for sliding it to and fro slightly in the direction of its axis so as to clean the platinum contacts by rubbing them together or for giving the electrode a partial turn so as to bring a new pair of contact surfaces into operation. Rotation of the movable electrode while in use is prevented by the end of the striking rod never being withdrawn quite clear of the slot or groove j' in the crown piece j with which it is coöperating for the time being.

30 The detachability of the magnet part from the plug part of the device also enables the apparatus to be inserted for example through a hole in the water jacket and screwed into the cylinder by means of a box spanner applied over a suitably formed part e^3 of the body of the plug.

The insulated end of the magnet coil l is secured between a clamping plate m and a terminal block n which is attached to but insulated from the magnet, and has a conical socket n' for the reception of the spring ends o of a split pin in the eye o' of which the flexible connecting lead p has been secured by stripping the insulation from the end, doubling the free ends of the conductor strands on themselves, inserting the bunched end of the flexible lead in the eye and pinching or cramping the latter to grip the lead tightly.

Having thus described the nature of this 50 invention and the best means I know of carrying the same into practical effect, I claim:

1. An electrical ignition apparatus of the low tension type comprising a tubular magnet, an armature carrying a striking rod extending through the bore of said magnet, a hollow sparking plug having a fixed electrode, and a movable electrode actuated by the striking rod and extending longitudinally through and fulcrumed to move transversely within said hollow plug; substantially as described.

2. An electrical ignition apparatus of low tension type comprising a tubular magnet, a 65 non-magnetic tubular extension, an arma-

ture carrying a striking rod extending through the bore of said magnet, a hollow sparking plug having a fixed electrode, and a movable electrode actuated by the striking rod and extending longitudinally through and fulcrumed to move transversely within said hollow plug; substantially as described.

3. An electrical ignition apparatus of the low tension type comprising a tubular magnet, an armature carrying a striking rod adjustably secured thereto and extending through the bore of said magnet, a hollow sparking plug having a fixed electrode, and a movable electrode actuated by the striking rod and extending longitudinally through and fulcrumed to move transversely within said hollow plug; substantially as described.

4. An electrical ignition apparatus of the low tension type comprising a tubular magnet, an armature carrying a striking rod extending through the bore of said magnet, a hollow sparking plug having a fixed electrode, and a movable electrode actuated by the striking rod and extending longitudinally through the plug and having a fulcrum comprising a ball and socket joint adapted to prevent the leakage of the working fluid, said movable electrode adapted to move transversely within said hollow plug; substantially as described.

5. In an electrical ignition apparatus of the character described, a movable fulcrumed electrode having a plurality of contact studs and adapted to be rotated to bring any desired stud into the operative position, means normally operative to prevent rotation of said electrode and means permitting the displacement of the aforesaid means and the rotation of said electrode; substantially as described.

6. In the apparatus of the character herein described a striking rod and a movable electrode having a multiple contact piece at one end, and a plurality of radial grooves at the other end adapted to coöperate with the striking rod to deflect the electrode, while preventing rotation thereof; substantially as described.

7. In the apparatus of the character herein referred to, a tubular magnet, an armature carrying a striking rod a movable electrode actuated by, and inclined slightly axially with respect to the striking rod, and a returning spring encircling the rear part of the body of the electrode and compressed between a fixed abutment on the electrode and a slidably abutment thereon; substantially as described.

In testimony whereof I have signed my name to this specification in the presence of two subscribing witnesses.

JOHN ARTHUR TORRENS.
